 N. Y., a corporation of Maryland

Application August 27, 1932, Serial No. 630,643

9 Claims. (Cl. 164—28)

This invention relates to the manufacture of covering units such as shingles and shingle strips and to the apparatus used in such manufacture.

In the manufacture of covering units of various types made from sheet material, and especially from the sheet material commonly known as roofing, it has been the practice to feed a sheet of the roofing material into a machine or a series of machines for cutting the sheet into units in the form of individual shingles or shingle strips or units of various shapes for covering surfaces generally in overlapping arrangement, particularly surfaces exposed to the weather. In order to provide uniformity of the dimensions of such shingles or shingle strips or covering units, it has been the practice to mount in the machine, cutting and marking devices which are mechanically or otherwise inflexibly connected or geared together and to the means for continuously delivering the sheet to said cutting and marking devices. By this means under some conditions a more or less uniform product as to the dimensions of the units in the direction of the motion of the sheet and as to marks which are placed upon the units for certain purposes, such as guides for laying the units in the overlapping arrangement, may be produced.

Because of the inflexible arrangement of the mechanisms, it has not heretofore been possible to adjust the relations of the parts, particularly the cutting and marking parts, with respect to each other or to the feeding mechanism so as to compensate for the effect of variations in the character of the sheet material. These variations may occur due to differences or changes in the fabric of the sheet or its degree of saturation with asphalt or other bituminous material customarily used. They may also be due to atmospheric conditions or other causes. Such variations in the character of the sheet produce a shortening or lengthening effect thereof and thus make it impossible to secure constant dimensions of the units or constant distances between the cuts and the marks or between two different marks upon the sheet. Moreover, heretofore no provision has been made for easy and accurate adjustment of the relation of the parts to change the distance between the cuts or the marks made upon the units or of the relation of the marks to the dimensions of the units.

The present invention has for one of its objects the provision of means for compensating for the variations in the delivery of the sheet or due to changes in its structure.

A further object of the invention is to adjust

at will the distances between the marks upon a strip or between an edge of such a unit and a mark thereon.

Another object of the invention is to provide a mechanism for varying the position of a mark or cut upon a roofing sheet while the marking and cutting machine is in operation.

In the mechanism arranged according to my invention I provide for a differential relation or setting of one of the members of the mechanism which effect the cutting or marking with respect to another of these members or with respect to the mechanism for feeding the sheet through the machine. For example, in those machines which are constructed with a feed or tractor roll which causes delivery of the sheet through the machine, and which machines are also provided with a second roll such as a marker roll for making a mark or indentation upon the moving sheet, I provide a mechanism connected to both the tractor roll and the marker roll so as to cause a differential rotation of one of these members with respect to the other. This differential rotation may be produced by the mechanism of my invention when either one of these rolls is stationary and the other moved with respect to it. Moreover, my mechanism is so arranged in connection with the tractor and marker rolls that the differential motion may be brought about while the machine is in operation; that is, the rolls themselves are rotating upon their axes.

According to my invention, if a tractor roll feeds a sheet at a uniform rate and if a marker roll is arranged to mark the sheet at intervals along the length of the sheet by causing a marking edge or knife to press upon or cut into the sheet, for example, once in each rotation, the position of the mark upon the sheet with respect to a given point thereon which has been delivered by the tractor or feed roll may be changed by a differential motion of the marker roll with respect to the tractor roll. My invention, however, is not limited to those machines which use rolls for delivery of the sheet and which use rolls having knives or markers thereon for cutting or marking the sheet, but the invention may be applied to machines which effect the delivery or the marking or cutting operations by reciprocating or other mechanisms. In the various machines to which it is applied, the mechanism of my invention provides for a differential movement of one member with respect to the other to vary the spacing lengthwise of a sheet fed through the machine of marks or cuts spaced along the sheet in the direction of its motion.

The invention will be more clearly understood from the description thereof to follow in connection with the drawings, of which:

Fig. 1 shows in diagrammatic form the arrangement of the members of the roofing machine or of the cutting machine to produce shingles or shingle strips or similar units;

Fig. 2 shows a diagrammatic arrangement of the epicyclical gear train and the indexing devices of the invention;

Fig. 3 is a diagrammatic developed plan view of the mechanism of Fig. 1;

Fig. 4 shows a plan view of the mechanism applied to a shingle cutting machine; and

Fig. 5 shows a side elevation of the machine of Fig. 4;

Figures 6 and 7 and Figures 8 and 9 show two modifications of the differential mechanism of the invention.

Figure 10 shows a modification of the driving connection between the parts.

In Fig. 1 a roll of roofing material which in ordinary practice is made from a sheet 1 of roofing felt impregnated with asphalt and having a coating of asphalt on one side thereof, upon which coating is applied a surfacing of slate granules, is shown at 2 mounted so as to turn freely upon the shaft 3 under suitable control. The sheet 1 as it unrolls passes in contact with the tractor rolls 4 and 5 which draw the sheet 1 from the roll 2. The pressure is maintained between the two rolls 4 and 5 by suitable means so as to provide the necessary tractive effect upon the sheet. In the arrangement shown the sheet then passes under the slitters 10 and 12 mounted on the shafts 11 and 13 to slit the sheet longitudinally into strips or bands. The slitting operation, however, may be done at another point in the series of operations accomplished in this machine or in certain cases may be omitted if the full width of the sheet is to be utilized in forming the units.

As 15 is shown a marking cylinder mounted on the shaft 16, the shaft 16 being driven at a speed such that the circumferential movement of the cylinder 15 corresponds with the movement of the sheet produced by the tractor rolls. A marking knife, diagrammatically shown at 17, is mounted upon the circumference of the cylinder 15 and acts against the counter surface 18 known as the anvil mounted upon a roll 19 suitably positioned on the underside of the sheet. The roll 19 is suitably geared to the cylinder 15 to bring the knife edge 17 in contact with the sheet when the anvil is in a position immediately upon the other side of the sheet so as to receive the pressure of the marking knife 17. The position of the marking knife 17 upon the cylinder 15 and of the anvil 18 upon the roll 19 lengthwise respectively of the cylinder and of the roll and the form of the marking knife and the corresponding anvil may be such as to produce a mark or a cut in the sheet of desired form and length and in the desired position laterally of the sheet 1 or of the longitudinal strips or bands into which the sheet may have been cut by the slitter 10. It will be clear, when the rolls 4 and 5 are suitably geared together and the cylinder 15 and the roll 19 are also suitably geared together and that between these geared members a train of gears is connected or a connection made as by a chain drive, that for each revolution of the tractor roll 4, the cylinder 15 and the counter roll 19 will make a definite number of revolutions. Thus if the sheet is of uniform character or texture as delivered by the tractor rolls 4 and 5, a mark or cut will be

made by the knife 17 at definitely spaced intervals lengthwise of the sheet or of the strips cut therefrom.

If the sheet or the strips or the bands are to be cut into individual units of limited length, this may be accomplished by providing a cutting roll 25 having a cutting knife 26 mounted thereon and arranged to bear upon a counter or anvil 27 mounted upon a counter roll 28. The cutting roll 25 and the counter roll 28 are respectively mounted upon shafts 30 and 31. In present practice these rolls also are directly connected as by gearing to the tractor rolls and therefore to the marking cylinder 15. If the sheet is of uniform character, the longitudinal strips or bands of the sheet will be cut into units of definite length upon each revolution of the rolls 25 and 28. By suitably positioning the knife 26 and the counter 27 with respect to the rotation of the marking knife 17 and its counter 18, which positioning may be accomplished by proper meshing of the teeth of the connecting gearing, the cutting of the bands into unitary shingles or strips will be effected so that the marks made by the marking knife 17 will be in a more or less definite relation to the edges cut by the knife 26.

In order to compensate for variations in the character of the sheet and particularly to change the relation of the marks and cuts, for example the relation of the mark made by the marking knife 17 with respect to the edge cut by the knife 26, according to my invention I provide a mechanism by means of which the cylinder 15 and its counter roll 19 geared thereto may be conveniently turned respectively upon the shafts 16 and 35 20 with respect to the other members such as the tractor rolls and the cutting rolls.

In one embodiment of my invention which, for simplicity, I will now describe, I so arrange gearing connected to the members as to produce 40 a differential motion between the tractor rolls 4 and 5 and the cylinder 15 and its counter roll 19 in order to change the position of the marking knife 17 with respect to a point upon the sheet which has been delivered by the rolls 4 and 45 5. It will be understood that such a point delivered by said rolls may be the point at which the longitudinal strips or bands are to be cut to form the units or it may be a point at which a second mark may be placed in the sheet. It will be clear 50 that the movement of the marking knife 17 with respect to the tractor rolls 4 will move the position of the mark set in the sheet or in the bands with respect to such a point as delivered by the rolls 4 and 5. If, for example, the point upon 55 the sheet at which the sheet is in contact with the rolls 4 and 5 is considered as such a point and if at the same time the marking knife 17 and its counter 18 are in contact with the sheet, then the distance between the point in question and the mark set by the marking knife 17 will be the distance between the vertical center line of the rolls 4 and 5 and that of the cylinder 15 and the roll 19.

If now by means of the differential mechanism 65 of my invention the cylinder 15 carrying the marking knife 17 is moved to the position shown in Figure 1, it will be evident that the mark will have been made in the sheet at 21 which will be in a position to the right of the point of 70 contact of the sheet with the cylinder 15. Thus the distance between the above referred to point on the sheet, which may correspond to a second mark or to a cut edge of the unit, and the mark produced by the marking knife 17 will be less 75

than that produced as first described. Correspondingly, if the marking knife 17 upon the cylinder 15 is moved to the left of the vertical center line of the cylinder 15 by differential rotation of the cylinder 15 with respect to the tractor rolls 4 and 5, the distance between the point in question upon the sheet, such as the point in contact with the rolls 4 and 5 and the mark set by the marking knife 17, will be greater than as first discussed. The detail of the mechanism for producing this differential rotation of the cylinder 15 and its counter roll 19 with respect to the tractor rolls 4 and 5 will be described hereafter.

It will be understood that if the cutting rolls 25 and 28 are directly connected to the tractor rolls 4 and 5 so that the differential rotation of the cylinder 15 does not change the relation of the cutting rolls 25 and 28 with respect to tractor rolls 4 and 5, the position of the mark made by the marking knife 17 will be altered with respect to the edge or cut made by cutting rolls 25 and 28. Thus the position of the mark will be changed with respect to the edge of the individual units which are produced by the machine. It will also be clear that if for the cutting rolls 25 and 28 are substituted a second marking cylinder and its counter roll similar to that provided by the cylinder 15 and the roll 19 respectively with the marking knife and anvil, the space between two marks upon the unit may be changed by the differential rotation of the members as described.

Moreover, if two marking devices are directly connected together without the means of effecting differential motion therebetween, it may be seen that while the space between the two marks made by said marking devices will be maintained constant, the position of both of the marks may be changed with respect to a point delivered by the tractor rolls 4 and 5. Thus both marks would be changed with respect to the edge cut by the cutting rolls 25 and 28.

In describing the above diagrammatic arrangement of the parts of the roofing machine to which my invention is applied, reference has been made to the use of differential mechanism or mechanism for producing the differential rotation of the marking knife or cutting knife with respect to the tractor roll or with respect to each other. Broadly, my invention resides in the combination with the ordinary means for moving a roofing sheet through a machine for cutting roofing units and for making marks or cuts in the roofing sheet of means to produce units with differently spaced marks thereon or to vary the position of a mark upon the sheet with respect to a given point thereon. This I accomplish by causing a differential motion of the member which makes the mark or the cut with respect to the member which causes movement of said point with respect to which the mark is made in the sheet, or by causing differential motion of a plurality of marking or cutting members with respect to each other. While broadly my invention includes any means which will produce this differential change in the members having these different functions, I have found that I may make a simple embodiment of the invention without expensive change in the ordinary machines for the manufacture of roofing units or shingles or shingle strips by connecting a differential gear train to the tractor roll and to the marking cylinder or to any other two members

between which it is desired to produce the differential motion.

I have found that a particularly simple and inexpensive embodiment of this invention may be made in connection with shingle cutting machines by using an epicyclic gear train mounted upon the marker shaft or a shaft directly connected thereto and so connected as to produce the differential motion between said marker shaft and, for example, the tractor roll or the cutting rolls.

In Figures 2 and 3 is shown an arrangement of gearing connected to two marking cylinders 40 and 41 having mounted thereon marking knives 42 and 43 respectively. These marking cylinders 40 and 41 are respectively mounted upon shafts 15 5 and 10 44 and 45. Keyed to the shaft 44 is the sprocket 53 which is connected by means of the chain 51 to the sprocket 52 which is mounted upon the shaft 45 but turns loosely thereon. Fastened to the sprocket 52 and turning therewith loosely upon the shaft 45 is mounted the spur gear 55. Upon the shaft 56 and keyed thereto is mounted the spur gear 57. Upon this shaft also and keyed thereto is mounted the spur gear 58 meshing with the spur gear 59 which is keyed upon the marker 25 shaft 45. Brackets or arms 65 and 66, Fig. 3, are mounted with bearing portions 67 and 68 loosely upon the marker shaft 45. At the outer ends of the brackets or arms 65 and 66 are provided bearings 69 and 70 in both of which is journaled 30 the shaft 56. These brackets thus position the shaft 56 with respect to the marker shaft 45 and maintain respectively the gears 55 and 57 and 58 and 59 in mesh. It will be clear that the shaft 56 may revolve into parallel positions around the 35 shaft 45 and that the gears 57 and 58 respectively will roll upon the gears 55 and 59.

The gears 55 and 59 are of unequal size and number of teeth and correspondingly the gears 57 and 58 are of different size and number of 40 teeth. In the well known manner of epicyclic gear trains it will be clear that when the shaft 56 is revolved about the shaft 45, assuming the shaft 45 to be stationary for simplicity of explanation, the periphery of the gear 58 will be rolled upon 45 and measured upon the periphery of the gear 59. If, for example, the gear 58 has 16 teeth and the gear 59 has 25 teeth, the gear 58 will roll approximately 1.56 times upon the gear 59. This motion of rolling will cause the shaft 56 to turn 1.56 50 times upon its axis, that is, with respect to its bearings 69 and 70. The gear 57, which is keyed upon the shaft 56, must turn also an equal number of turns while likewise it is rolling upon the gear 55.

If the gear 57 has 20 teeth, properly to mesh with teeth of the same pitch, the gear 55 must have 21 teeth. In one revolution of the shaft 56 the gear 55 would then make 20/21 of a rotation. In making 1.56 turns of the shaft 56 upon its axis the gear 55 would then make 1.49 rotations upon its axis. Due to the effect of the revolution of the shaft 56 about the shaft 45, this ratio however must be corrected as will now be explained.

To make the action clear, let it be supposed that in revolving the shaft 56 about the shaft 45 the gears are locked together so that they do not rotate one with respect to the other. If after one revolution of the shaft 56 about the shaft 45 has been made, which it will be understood involves a rotation of both the gears 59 and 55 about the axis of the shaft 45 when the gears are locked together, the shaft 45 and the gear 59 keyed thereto are rotated in a reverse direction one turn to restore the gear 59 and the shaft 45 75

to the original position before revolution of the shaft 56, then it will be seen that the gear 55 also must rotate reversely and must make 1.49 rotations with respect to the gear 59 and the shaft 45. 5 However, as the gear 55 has been given one rotation in the forward direction, the net result of the two movements will be .49 of a rotation of the gear 55 with respect to the gear 59 and the shaft 45 in one revolution of the shaft 56 about the shaft 45. The shaft 44, being directly connected and geared to the gear 55 through the sprocket 52 having 21 teeth and the sprocket 50 having 20 teeth, will make 21/20 times .49 rotation for each revolution of the shaft 56 about the shaft 45. The shaft 44 will then rotate .52 of a turn upon its axis.

It will be noted that with the gear ratios used in the above example, the gear 55 will move .49 of a rotation with respect to the shaft 45 in a direction of rotation opposite to that of the revolution of the shaft 56 about the shaft 45. By using different ratios or numbers of teeth on the different gears, it will be possible to rotate the gear 55 in the same direction as the shaft 56 about the shaft 45. However, for most purposes in the application of the invention to machines for cutting and marking shingles or shingle strips, any convenient ratio may be adopted to suit the mechanism of the particular machine because, in the manner to be described, the differential gearing of my invention may be conveniently rotated in either direction in a greater or less degree as desired.

It will be understood that the above description of the relative motion of the parts assumes that the shaft 45 is stationary. However, if rotation is given to the shaft 45, as occurs in the operation of the cutting machine, and thereby through the gearing shown and described rotation is also given to the shaft 44, the differential action likewise may be produced by moving the shaft 56 about the shaft 45. As the shaft 56 may be revolved about the shaft 45 into parallel position, rotation of the shaft 45 does not prevent the rolling of the gears as described. Thus the differential rotation of shaft 45 with respect to shaft 44 and therefore respectively of the marking knives 42 and 43 may be produced while the machine is in motion. The differential motion provided by the mechanism and described in connection with Figures 2 and 3 will produce the result of varying the spacing of the marks produced by the knives 42 and 43 without the necessity of stopping the machine to reset the members.

If the marking knives 42 and 43 are positioned at points on the circumference of the marking cylinders 40 and 41 at which the sheet being marked is tangent, then the space between the marks made by knives 42 and 43 upon the sheet is equal to the center line distance between the shafts 44 and 45. If, now, by means of the differential gearing marking cylinder 40 is rotated with respect to the marking cylinder 41 so that the marking knife 42 assumes the position indicated at 75, then the distance between the marks upon the sheet will be less than the center line distance between the shafts 44 and 45. Correspondingly, if the gearing is rotated in the opposite direction by the opposite movement of the shaft 56, the marking knife 42 may assume the position 76 and the space between the marks upon the sheet will be increased.

To produce the rotation of the shaft 56 about the shaft 45 by simple means, in one embodiment of the invention I provide a gear 80 mounted upon

the shaft 45, but turning loosely thereon. This gear is fastened near its periphery to one of the bearings, such as the bearing 78 supporting the shaft 56, or is made integral with the arm 66 and its bearings 68 and 70, so that a rotary movement given to the gear 80 will produce a rotation of the arm 66 and bearing 70 about the shaft 45. Thus the shaft 56 is caused to revolve about the shaft 45.

In order conveniently to produce the motion of the gear 80, I provide a shaft 85 having keyed thereto at one end thereof a pinion 86 meshing with the gear 80. Upon said shaft, conveniently at the end thereof opposite to the end at which the pinion 86 is fastened, is keyed a lever 87 having a handle 88. Fastened to a suitable stationary support 90 by means of fastening bolts 91 is mounted an index dial 92 having holes 93 spaced circumferentially thereon. An arm 94 upon the lever 87 is provided with an index pin 95 which may be withdrawn or inserted in the holes 93 by means of the handle or head 96. When the pin 95 is withdrawn from a hole 93, the lever 87 may be rotated by hand, thus rotating shaft 85 and the pinion 86 keyed thereto. The pinion 86 thus gives motion of rotation to the gear 80 about the shaft 45. This motion is transmitted to the shaft 56 which is thus caused to revolve about the shaft 45, and the differential motion of the marking cylinders 40 and 41 is produced. It will be understood that by suitably designing the parts a very slight motion may be given to the marking knives 42 with respect to the marking knife 43, or a considerable movement of one with respect to the other may be effected. In the practical embodiment, for example, the pinion 86 may have 15 teeth and the gear 80 may have 75 teeth. Thus one revolution of the pinion will produce only $\frac{1}{5}$ of a revolution of the gear and only $\frac{1}{5}$ of a revolution of the shaft 56 about the shaft 45. By subdividing the index head into a suitable number of parts by means of the spaced holes, further fractional movement of the shaft 56 about the shaft 45 may be accomplished, or by giving to the handle 88 and lever 87 a plurality of revolutions, the complete revolution of the shaft 56 or several revolutions thereof may be produced.

It will also be understood that in the operation of the machine the shaft 56 is not in motion about the shaft 45, and the gear 80 and the pinion 86 meshing therewith are also stationary. Thus no provision need be made for the continuous rotation of the shaft 85. The movement of the shafts 44 and 45 in the normal operation of the machine is accomplished by transmission of the motion from one to the other through the chain drive and through the gears 55, 57, 58 and 59. Either direction of transmission of the power for normal motion, of course, is possible while providing for the differential movement described. In the particular embodiment illustrated, the rotation of the shaft 45 with respect to the shaft 44 would be represented by the product $20/21 \times 21/20 \times 16/25$. Thus for each revolution of the shaft 44 in normal operation the shaft 45 would move $1/1.56$ revolutions. The diameters of the marking cylinders 40 and 41 respectively may be so chosen as to provide the proper circumferential movement of the marking knives 42 and 43 to correspond with the linear movement of the sheet passing in contact with said cylinders. The differential rotations temporarily change the relation of the revolutions during the time of adjustment but do not change the ratios or circum-

ferential rates of delivery in changing the spacing of the marks.

In Figures 4 and 5 is shown a somewhat diagrammatic arrangement of the differential gearing combined according to my invention with a shingle cutting machine of usual design. In Figures 4 and 5 the reference numerals so far as possible are made to correspond with Figures 1, 2 and 3. The roll of roofing material, which is shown at 2 in Figure 1 but not shown in Figures 4 and 5, is mounted in the usual manner and arranged so that the sheet 1 may be fed through the machine in the direction of the arrow. The sheet 1 in the embodiment of Figures 4 and 5 passes between the marking rolls 15 and 19 and through the slitters 10 and 12, the sheet being drawn through these parts of the machine by the tractor rolls 4 and 5 mounted upon the shafts 6 and 7 respectively. Upon the shaft 7 is mounted the sprocket 100 upon which runs the chain 101 transmitting the motion to the cutting rolls (not shown) which correspond to the cutting rolls 25 and 28 in Fig. 1.

The rolls 15 and 19 are respectively mounted upon the shafts 16 and 20. These shafts turn in bearing blocks 105 and 106 slidably mounted between the portions 107 and 108 of the frame of the machine. Suitable mechanism is provided to transmit from the hand wheel 110 to the screw 111 power to move the block 105 and thus position the marker roll 15 properly in relation to the counter surface upon the roll 19. The slitter knives 10 and 12 are similarly mounted in bearing blocks which similarly may be positioned by means of a hand operated mechanism.

The tractor rolls 4 and 5 are carried on shafts 6 and 7 which are similarly mounted in bearings on the frames 115. These bearings for simplicity of illustration are omitted in Figure 5. In the arrangement of the shingle cutting machine shown in Figure 4, power is applied by means of a belt 120 to the pulley 121 keyed to the extension of the slitter shaft 13. Also keyed to the shaft 13 is the sprocket 122 upon which runs the chain 123 passing over the sprocket 124 which is keyed upon the shaft 20 of the marker roll 19. Thus the motion of rotation which is given to the shaft 13 when the power is applied to the belt 120 causes motion of the marker rolls 15 and 19 in a fixed relation.

In Figure 4 the arrangement of the differential gearing is shown to provide for a differential motion of the tractor rolls 4 and 5 with respect to the marker rolls 15 and 19. Upon the extension of the shaft 13 is keyed the gear 59. Also mounted upon this shaft to swing loosely thereon are the arms 65 and 66 carrying the auxiliary planetary shaft 56 upon which are keyed the gears 57 and 58. The gear 58 meshes the gear 59 and the gear 57 meshes the gear 55 running loosely upon the shaft 13. Upon an extension of the gear 55 is fastened the sprocket 52 connected by the chain 51 to the sprocket 50 fastened upon the shaft 7 of the tractor roll 5. It will be noted that there is thus provided a train of gears similar to that described in connection with Figures 2 and 3.

In the arrangement in Figure 4 the brackets are mounted at either side of the gear 80 which meshes with the pinion 86 upon the adjustment shaft 85 but the mechanism for adjusting the position of the shaft 56 about the shaft 13 is similar to that shown in Figures 2 and 3 and the parts bear like reference numerals. Motion of revolution of the shaft 56 about the shaft 13 thus

moves the gear 55 and its sprocket 52 and likewise the sprockets 50 and 100 simultaneously with respect to the shaft 13 and to the sprocket 122 keyed thereto and therefore correspondingly simultaneously with respect to the sprocket 124 mounted on the shaft 20. It will thus be understood that in the embodiment shown in Figures 4 and 5 the tractor rolls 4 and 5 and the cutting rolls (not shown) driven through the chain 101 will be rotated upon their axes with respect to the slitters 10 and 12 and to the marker rolls 15 and 19. Thus the sheet will be drawn by the tractor rolls through a fraction of its length or will be retarded a fraction of its length during a revolution of the marker rolls 15 and 19 depending upon the direction of motion of the shaft 56 about the shaft 13. The length of the units cut by the cutter rolls which are driven through the sprocket 100 and the chain 101 will not be changed because the relation of the cutters to the tractor rolls is unchanged. The adjustment of the tractor rolls and likewise the cutter rolls with respect to the marker rolls may be made while the machine is in operation in the manner explained in connection with Figures 2 and 3.

Various modifications of my invention may be made without departing from the spirit thereof. Instead of epicyclic gear trains as shown in the Figures 2, 3, 4 and 5, I may provide internal or planetary gears or combinations of gears and chain drives or other mechanisms which may be designed for differential motion of moving or rotating parts. For example, in Figures 6, 7, 8 and 9 there are shown arrangements of internal or planetary gears arranged to produce the differential motion of the shaft 44 with respect to the shaft 45. In the illustrations of these embodiments of the invention parts having like function to those of the mechanisms of Figures 2 and 3 bear reference numerals as in Figures 2 and 3. Thus, in Figures 6 and 7 the normal drive applied to the shaft 45 for example, turns the gear 59 meshing with the gear 58. The gear 58 is keyed to a stud shaft 56 having a bearing in the web of the gear 80. Also keyed to the shaft 56 is the gear 57 meshing internally with the gear 55.

The sprocket 52 is made integral with the gear 55 as in the embodiment illustrated in Figures 2 and 3. The chain 51 connects the sprocket 52 to the sprocket 50 on the shaft 44. By suitable selection of the diameters of the respective gears and of the sprockets the desired speed relation between shafts 44 and 45 may be secured. Moreover, as the gear 80 is loosely mounted on the shaft 45, upon rotation thereof the shaft 56, carrying gears 57 and 58 may revolve as a whole about the axis of the shaft 45 in the same manner as described in connection with Figures 2 and 3. By suitably selecting the ratios of the gears the differential rotation of the gear 55 and of the sprocket 52 with respect to the shaft 45 may be produced as in the mechanism described in Figures 2 and 3, thus causing differential rotation of the shafts 44 and 45. Similarly, by means of planetary beveled gears, as illustrated in Figures 8 and 9 the differential motion of these shafts also may be secured. Within the scope of my invention I may also combine my mechanism with other means for insuring rotation of the respective marking or cutting members. For example, as shown in Figure 10, if the shaft 44 is driven by a direct connected motor 140 and the gear 55 is likewise driven through

suitable connection by a second motor 142 operating in substantially a constant relation to or in synchronism with the first motor, as may be accomplished by connecting said motors to a common source of electric power through the switch 144, it will be clear that a differential motion of the shaft 45 with respect to the shaft 44 may be accomplished by the mechanism described in like manner to that produced when the drive connection is provided by the chain 51 connecting the sprockets 59 and 52. Other modifications will be apparent to those skilled in the art while practicing the invention in the utilization of mechanism for producing a differential change or movement of the two members which cause the marking or cutting of the sheet at spaced points or of members which feed and mark the sheet. All such modifications and uses are within the scope of my invention.

Having thus described my invention, I claim:

1. In a shingle cutting machine, the combination with a pair of spaced rotary heads arranged for passage of a sheet of roofing material successively in circumferential contact therewith and having means on each of said heads for indenting the sheet, of means including a differential gear train connected between said heads for differentially rotating one head with respect to the other, said differential gear train having a pair of rolling gears connected together to rotate upon a common axis and arranged to be revolved as a whole about the axis of and respectively to roll upon the gears of the differential train which rotate upon the driving axis of the train, said rolling gears being of unequal pitch diameter.

2. In a shingle cutting machine, the combination with a pair of spaced rotary heads each arranged in circumferential contact with a sheet of roofing material moving successively in tangential relation to said heads, each of said heads having means on its circumference for indenting the moving sheet at intervals in the direction of motion of said sheet, of means including an epicyclic gear train connected to said heads and arranged to produce differential rotary movement of one head with respect to the other without change in the interval of repetition but with change of the space between the indentations made by said pair of heads, said gear train having the rolling gears of unequal pitch diameter to cause the gears rolled upon to rotate differentially with respect to each other.

3. In a shingle cutting machine, a pair of spaced rotary heads arranged for rotation upon parallel axes, means for delivering a sheet of roofing material into contact successively with the circumferences of said head, means for indenting the sheet mounted on each head, a gear arranged to turn loosely upon a shaft and to be rotated upon rotation of one of the rotary heads, a gear fastened to said shaft to rotate therewith, said shaft being arranged to rotate with rotation of the other rotary head, a pair of gears fastened together to rotate upon an auxiliary axis parallel to said shaft and respectively meshing with said gears, which are loose and fastened upon said shaft, and means for revolving about said shaft said auxiliary axis and said pair of gears rotatable together thereon, the pairs of meshing gears being of unequal ratio whereby is caused a differential movement of the gear loose upon said shaft with respect to the gear fastened upon said shaft and a circumferential movement of the indenting means of one rotary head with respect to that of the other.

4. In a machine for marking a continuous sheet of material moving in the direction of the dimension thereof in which said sheet is continuous, the combination with a pair of devices for marking the sheet each moving with the sheet and contacting the sheet at points spaced thereon in the direction of motion of the sheet, of a mechanism connected to said devices for differentially varying the motion of one device with respect to the other, said mechanism comprising a driving member rotating upon an axis and connected to one of said devices, a member rotating upon an axis and free of direct driving connection to said driving member but connected in driving relation to said other device, means rotating upon an axis not coincident with the axis of at least one of said members and so mounted and arranged that said means and its axis may be revolved as a whole about the axis of said member, said means being arranged for circumferential driving contact of a part thereof with said driving member and for circumferential driving contact with said free member of another part of said means connected to said first part to rotate therewith upon its axis, the ratios of the rotation of said parts in circumferential contact with said driving member and said free member respectively to the rotation of the driving and of the free members being unequal.

5. Apparatus comprising means for continuously moving a continuous sheet lengthwise thereof, means for marking said moving sheet at intervals lengthwise thereof in a given time relation selected from the relations of lag and lead with respect to the means for moving the sheet, and a mechanism for varying the time relation of said moving means and said marking means to vary the position of the marks upon the sheet lengthwise thereof, said mechanism for varying said time relation including a driving member rotating upon an axis and connected to one of said means selected from the group composed of the moving means and the marking means, means rotating upon an axis not coincident with the axis of said driving member and so mounted and arranged that it and its axis may be revolved as a whole about the axis of said driving member but with portions in circumferential driving contact respectively with said driving member and with a member free of direct driving connection to said driving member, said free member being arranged to be rotated upon an axis and in driving connection with the other of said means included in said group, the ratios of rotation of said circumferentially contacting portions of said rotating means to the rotation of their respectively contacted members being unequal.

6. Apparatus comprising means for continuously moving a continuous sheet lengthwise thereof, a pair of marking devices arranged in such spaced relation as to mark the sheet at points spaced lengthwise thereof, said devices being arranged to repeat said pairs of marks at intervals lengthwise of the sheet, a driving member arranged to rotate upon an axis upon motion of said means for moving the sheet and connected to drive one of said marking devices, a member rotating upon an axis and free of direct driving connection to said driving member but connected in driving relation to said other marking device, and means rotating upon an axis not coincident with the axis of at least one of said members and mounted to revolve

together with its axis about said axis of said member, said means rotating upon an axis being arranged for circumferential driving contact of a part thereof with said driving member and for 5 circumferential driving contact with said free member of another part thereof connected to said first part to rotate therewith upon its axis, the ratio of rotation of said part in contact with said driving member to the rotation of said driving member being different from the ratio of rotation of said part in contact with said free member to the rotation of said free member, whereby one marking device is caused to move differentially with respect to the other to vary 10 the spacing of the marks without affecting the intervals between the pairs of marks.

7. Apparatus comprising a pair of spaced rotary heads each arranged in tangential relation to a continuous sheet moving successively in circumferential contact therewith, each of said heads having means on its circumference for marking the moving sheet at intervals in the direction of motion of the sheet, and means comprising two gears connected and mounted to turn together upon a common axis and so that said gears and said axis may be revolved as a whole about the axis of a driving member connected in driving relation to one of said rotary heads, one of said gears meshing with a gear fastened upon said driving member, the other of said gears meshing with a gear member free to rotate upon the axis of said driving member but connected in driving relation to the other rotary 20 25 30

head, the ratios of the meshing gears in the two sets being unequal.

8. Apparatus comprising a pair of spaced rotary heads each arranged in tangential relation to a continuous sheet moving successively in circumferential contact therewith, each of said heads having means on its circumference for marking the moving sheet at intervals in the direction of motion of the sheet, means comprising two gears connected and mounted to turn together upon a common axis and so that said gears and said axis may be revolved as a whole about the axis of a driving member connected in driving relation to one of said rotary heads, one of said gears meshing with a gear fastened 5 10 15 upon said driving member, the other of said gears meshing with a gear member free to rotate upon the axis of said driving member but connected in driving relation to the other rotary head, the ratios of the meshing gears in the two sets being unequal, and means for revolving about the axis of said driving member said gears connected and mounted to turn together upon their common axis to effect a differential movement of said driving member with respect to 20 25 30 said gear member free to rotate upon the axis of said driving member to cause a differential movement of said rotary heads.

9. Apparatus according to claim 8 in which said means for revolving said gears about the axis of the driving member is provided with means for indexing the differential movement of said members.

ARTHUR S. PETERSON.
